UNITED STATES PATENT OFFICE.

ALBERT N. MORIN, OF PAWTUCKET, RHODE ISLAND.

PERMUTATION LOCK.

Application filed June 3, 1924. Serial No. 717,541.

This invention relates to a permutation lock adapted to lock two relatively rotating members in either of two or more positions relative to each other and in the present instance is shown as applied to a drum or cylinder for locking the same in either of two positions wherein a varying degree of tension is applied to a cable, one end of which is secured to the drum. While the invention in its present embodiment is shown as utilized for the purpose above described it is to be understood that the invention is in no sense limited to use in this connection but is adapted to be employed generally wherever a locking means of this general character is used such as for safes, strong boxes, etc., as well as for locking automobile parts, steering gears, and machine elements generally against use by an unauthorized person.

One object of the present invention is to provide a simple and inexpensive structure of the character described which is efficient in operation and excellently adapted for use generally wherever a lock of this character may be used.

Another object of the invention is to provide a simple and efficient lock of the character described for locking a rotating member against rotation. A further object of the invention is to provide a locking means for securing a rotating member against rotation which comprises one or more radially movable elements.

Other objects and advantages of the invention relate to certain improved details of construction and improved methods of operation as will be more fully set forth in the detailed description to follow.

Referring to the drawings:

Fig. 1 is a side elevational view of my improved lock structure illustrated as applied to the instrument board of an automobile.

Fig. 2 is a front elevational view of the structure shown in Fig. 1, a portion of the front plate being broken away to show the position of certain of the parts.

Fig. 3 is a vertical sectional view taken along the line 3—3 of Fig. 1.

Fig. 4 is a vertical sectional view taken along the line 4—4 of Fig. 3, and

Fig. 5 is a detail perspective view of certain of the parts.

In the embodiment of the invention illustrated herewith 1 designates the instrument board of an automobile to which the annular shoulder 2 of the casing 3 is secured by suitable securing devices such as screws 4, the heads of the screws 4 being concealed from view by the annular shoulder 5 of the cylinder 6 whereby the removal of the screws 4, except by first removing the cylinder 6, is prevented.

The casing 3 is provided with an end plate 7 which is firmly secured in place by any suitable means such as by attachment to the flange 8 of a curved securing plate 9 fitting within a cylindrical member 10 to which it is secured by screws 11. Rivets 12 may be employed for securing the end plate 7 to the flange 8 as shown in Fig. 4. Thus the cylinder 6 is rotatably mounted between the casing 3 and the cylindrical member 10 in such a manner that it is capable of rotating freely therebetween.

The cylinder 6 is provided at one end with an annular shoulder 5 and the opposite end thereof terminates short of the end plates 7 as indicated by the numeral 14. A curved filler plate 16 is inserted between the interior surface of the casing 3 and the end portion of the cylindrical member 10, and the casing, cylindrical member and filler plate are firmly secured together by rivets or other suitable securing devices 17 as shown in Fig. 3. By means of the structure described the casing 3, cylindrical member 10 and end plate 7 are firmly secured together in such a manner that none of the fastening devices for securing the parts together are normally accessible for removal from the exterior of the casing.

The casing 3 is provided with a narrow opening 18 formed adjacent to the end portion thereof to which the end plate 7 is secured, and a lip 19 extends outwardly from the casing along the edges of the opening to prevent access to the casing. A rod 20 extends through the opening 18 and has one end thereof pivotally secured to a pin 21 carried by a lug 22 which is in turn secured to the end of the cylinder 6 by rivets or other

suitable fastening devices 23. The rod 20 is offset rearwardly of the end 14 of the cylinder 6 and in alignment with the opening 18, and, as will be seen upon references to Fig. 3 of the drawings, rotation of the cylinder 6 relative to the casing may draw the rod into the position shown in Fig. 3 or by rotating the cylinder 6 in a clockwise direction as seen in Fig. 3 the pin 21 may be 10 carried through 180° so that the rod 20 is substantially entirely without the casing. The cylindrical member 10 is cut away as indicated by the line 24 throughout somewhat more than 180° of its circumferential 15 extent thereby providing space for the movement of the lug 22 secured to the inner face of the cylinder 6, and providing shoulders 25 and 26 for engagement by the lug 22 to limit the movement of the cylinder 6 and 20 lug 22 carried thereby in each direction.

With this arrangement of the parts the cylinder 6 may rotate through substantially 180° and the rod 20 secured thereto may be drawn into the position shown in Fig. 3 25 or turned so that it is substantially entirely without the casing.

The annular shoulder 5 of the cylinder 6 is provided upon its outer face with a plurality of radial grooves 26, in the present 30 instance four in number, although a greater or less number of grooves may be provided as may be desired, and a bolt 27 is slidably mounted in each groove 26 for the purpose of locking the cylinder 6 in any one of a 35 number of desired positions. The grooves 26 are preferably of sufficient depth so that when the bolts 27 are placed therein their upper surfaces are flush with the outer face of the annular shoulder 5. Each of the bolts 40 27 is provided with an enlarged head 28 and has formed on one side thereof a transverse slot 29 for a purpose which will be more fully described hereinafter. A plurality of depressions 30 are formed in the side of 45 each bolt 27 opposite that in which the slot 29 is formed, the depressions 30 cooperating with means now about to be described for holding the bolts against free sliding movement in the grooves.

50 A cover plate 32 is placed over the end of the cylinder 6 and secured to the annular shouldered portion 5 by screws or other suitable fastening means 33 which are inserted from the rear face of the shoulder 5 so that 55 they may not be removed from the exposed face of the cover plate. It is my purpose, however, in the practical application of the invention to make the cover plate portion integral with the shoulder 5 by casting or 60 otherwise forming the parts so that access cannot be had to the interior of the casing by prying off the cover plate. When the parts are formed integral as above described the grooves 26 may be formed by boring or in 65 other suitable manner and the provision of

threaded screws 35 will prevent removal of the bolts after the parts are assembled. A pin 34 is secured to the inner face of the cover plate 32 and projects inwardly therefrom to serve as a stop for limiting the inward movement of the bolts 27. A threaded screw 35 is threaded into one face of each bolt near the end thereof so that a portion thereof projects from the bolt to serve as a stop for preventing the bolt from being 70 entirely withdrawn from the groove. A recess 36 is formed in the cover plate opposite the path of movement of each bolt, and a ball 37 and spring 38 positioned in each recess whereby the spring pressed ball is forced 75 by the spring against the adjacent face of the bolt 27 to engage one or another of the depressions 30 and thereby releasably locate the ball successively in one or another of the depressions as the bolt is moved inwardly or outwardly in the groove 26. Each recess 36 has the metal around the mouth thereof drawn inward slightly after the spring 38 and ball 37 are inserted to prevent the escape of the ball in assembling the 80 structure. Each bolt 27 may be provided upon the face adjacent to the cover plate with a plurality of numbered lines to assist the operator in setting the bolts in accordance with a code of numbers, or letters or other indicia may be substituted for the numbers. In the present case four numbers are used for each bolt, each number having a line corresponding therewith, the numbers used being 1, 2, 3 and 4 as indicated at 85 40.

The cylindrical member 10 has formed therein, in the end adjacent to the cover plate, a plurality of notches 41 corresponding to the number of bolts employed. The bolts 27 slide in these notches 41 as the bolts are moved in the grooves 26 and when the several bolts are moved into position so that the transverse slots 29 of each bolt register with the corresponding notch 41 the cylindrical member 10 may be turned relative to the cylinder 6. At all other times these parts are held against rotation relative to each other by the bolts.

When the locking mechanism is in assembled position the only way in which access 115 may be had to the interior to remove the parts or make repairs is by first removing the screw 11 to which access may be had through the opening 42 in the casing and a similar opening 43 formed in the cylinder 6. These openings can only be brought into registry to permit of access to the screw 11 when the bolts 27 are placed in such position as to permit relative rotation of the cylinder 120 6 and the cylindrical member 10.

The rod 20, one end of which is pivotally secured to the cylinder 6 as at 21, has its opposite end secured to a chain or cable 44 as at 45.

In the operation of the structure above 130

described which in the present embodiment is shown as employed for the purpose of locking an automobile part in one or another of two positions, and more specifically for locking an alarm controlling mechanism such as is shown and described in my co-pending application Serial No. 717,542 filed June 3, 1924, in either of two different positions for preventing the sounding of the alarm or causing the same to be sounded upon movement of one of the operating parts by an unauthorized person, the cable 44 may be released by turning the cylinder 6 in a clockwise direction as seen in Fig. 3 to move the point 21 a distance of 180 degrees to the right of its position as shown in Fig. 3. The bolts 27 may be moved when the parts are in that position so that the slots 29 are no longer in registry with the notches 41 whereupon the parts are locked and cylinder 6 cannot be rotated relative to the cylindrical member 10 until the bolts are moved to bring the slots 29 and notches 41 into registry. If it is then desired to rotate the cylinder 6 in a counter-clockwise direction, as seen in Fig. 3 to bring the parts into the position shown in Fig. 3 with the cable 44 under tension, the bolts 27 are set in proper position by drawing them out until the slots 29 are in registry with the several notches 41, the proper position of the bolts being shown to one familiar with the combination by the position of the numbered lines indicated at 40.

The slots 29 are preferably located at different points upon each of the bolts so that the bolts are set at different numbers to permit rotation of the parts. After the bolts have been properly set the cylinder 6 may be turned in a counter-clockwise direction as seen in Fig. 3 until the parts are in the position shown in that figure. The bolts may then be all pressed inwardly or otherwise moved to such position that the several slots and notches are not in registry when the cylinder cannot be rotated by any person not familiar with the combination since all of the bolts must be in the correct position before rotation of the cylinder can be effected.

From the above it will be seen that the present invention provides a simple and efficient combination lock adapted for use for a variety of purposes and in many different arrangements of devices for locking bolts or moving parts in one or another of different positions, and when thus locked the parts can only be moved when the bolts 27 have been properly positioned by one familiar with the combination employed. The combination used may be changed at any time by substituting one or more bolts with differently positioned slots for those in use, and even by changing the arrangement of the bolts in use.

While I have shown and described my improved lock in connection with an automobile structure it is to be understood that the same is capable of general application and I do not desire or intend to be limited in its use to structures of any particular character except as the same may be specifically included in the appended claims.

What I claim is:

1. In a lock of the character described, a pair of telescoping cylindrical members fitting within a cylindrical casing and rotatable relative to each other, and radially disposed slideable members carried by one of said cylindrical members and each movable into any one of a plurality of adjusted positions for holding said cylindrical members against relative rotation while adapted to permit rotation of said cylindrical members when each of said slideable members occupies a certain position.

2. In a combination lock, a cylindrical casing, a pair of interfitting cylindrical members fitting within said cylindrical casing, one of said members being fixed and the other of said members being rotatable relative to said fixed member, a movable element, means secured to said movable member and movable therewith for moving said movable element, and bolts each radially disposed relative to said cylindrical casing and slideable across the path of movement of said movable member and movable into a plurality of adjusted positions for locking said movable member against movement relative to said fixed member or for releasing the same for movement relative to said fixed member.

3. In a lock of the character described, a casing, a pair of relatively rotatable members, an element secured to one of said members and adapted to be retracted within or projected from said casing upon rotation of said members relative to each other, and slideable bolts adjustable in accordance with a predetermined plan for permitting relative rotation of said members and movable thereupon to lock said element in either its retracted or its projected position.

4. In a lock of the character described, a cylindrical casing, a cylindrical member positioned within said cylindrical casing and fixed with relation to said casing, a cylindrical member fitting between said first named cylindrical member and said casing and rotatable relative to said fixed member, an element actuatable by said rotatable member for retraction within or projection from said casing, and means for locking said rotatable member relative to said fixed member.

5. In a lock of the character described, a cylindrical casing; a cylindrical member, fixed with relation to said casing, located within said casing and concentrically posi-

tioned relative thereto; a cylindrical member positioned within said casing and outwardly of said first named cylindrical member; said last named cylindrical member being rotatable relative to said first named cylindrical member, and a slid able member movable in a direction radially of the path

of movement of said rotatable member for locking said rotatable member against rotation relative to said first named cylindrical member. 10

In testimony whereof I have affixed my signature.

ALBERT N. MORIN.
